UNITED STATES PATENT OFFICE.

JOHN M. CROWE, OF COVINGTON, KENTUCKY, ASSIGNOR OF ONE-HALF TO LOUIS K. DE BUS, OF CINCINNATI, OHIO.

RIVET CATCHER.

Application filed June 19, 1920. Serial No. 390,221.

To all whom it may concern:

Be it known that I, JOHN M. CROWE, a citizen of the United States, residing at Covington, in the county of Kenton and 5 State of Kentucky, have invented certain new and useful Improvements in Rivet Catchers, of which the following is a specification.

This invention relates to improvements in 10 a casing for cutting tools, as for instance a rivet clipper, whereby the head which is clipped from the rivet is caught by the casing and thus prevented from striking a nearby workman.

15 One object of the invention is to provide a casing for the end portion of a cutting tool with a housing formed in the end of the casing to receive the clipped head of a rivet or the like.

20 Another object of my invention is to provide a rigid casing with a bearing strap or member extending across the open under side of the casing so that the cutting tool can move about a horizontal axis on said 25 bearing member and in this way make it possible for the cutting end of the tool to pass beyond the casing.

Still another object of my invention is to 30 form a rigid casing with flexible side portions and a flexible strap member connecting the edges of the side portions so as to allow the flexible portions to be gripped about the tool and to allow also the required amount of play for the tool as it moves about a 35 horizontal axis on the bearing member in passing beyond the casing end.

A further object is to provide a casing 40 with a metal rigid body portion and a covering of leather or other yieldable material, which projects below the edge of the metal at the bulged end so as to prevent the rivet head from slipping out between the casing and the tool.

Another object is to secure the yieldable 45 covering to the metal body portion in such a manner as not to interfere with the catching of the rivet head in the housing of the casing.

Other forms of structure embodying my 50 invention will suggest themselves to those skilled in the art, but the preferred form will be understood from the following description and claims considered in connection with the accompanying drawings.

55 Fig. 1 is a side elevation of my invention;

Fig. 2 is a longitudinal section;

Fig. 3 shows the casing in longitudinal section with the cutting tool and rivet head in elevation just prior to the clipping operation; and

Fig. 4 is a view like Fig. 3 showing the relative arrangement of casing and cutting tool after the rivet head has been clipped.

The casing comprises a concave rigid strip 1, of metal or other suitable material, to the outside of which is secured covering members 2 and 3 of flexible material, such as leather; these parts being secured together in any suitable manner, as for example by means of rivets 4 and 5. The forward end 70 portion of the casing is formed with a decided bulge as indicated at 9, so as to provide a housing for the reception of the severed head of a rivet or the like, as illustrated in Fig. 4. The member 2 is separate from 75 member 3 and is riveted along the back of strip 1 as at 4 so that the side portions 6 are free for flexure. The part 3 of the covering projects below the edge of the bulged portion 9, as indicated at 3^a in Fig. 2. With 80 this arrangement the material 3^a being yieldable, affords added protection inasmuch as the rivet head catcher accommodates itself to the irregularities of the material, thus preventing rivet heads and steel slivers from 85 flying, and furthermore permits the rivet head catcher to be moved forward or backward with greater facility. The rivets for securing the covering 3 to the metal member 1 are placed away from the front end 90 of the casing, as for instance along the sides as at 5, so as to avoid any danger of the severed rivet head striking a head of one of these rivets 5 and glancing out between the casing and the cutting tool as above referred to. Thus the covering 3 is extended back over the bulged end of the member 1. The covering 3 is split and overlapped as at 95 3^b and 3^c so as to conform to the shape of the housing.

A curved strap or bearing member 7 has its ends attached to the side portions 6 in any suitable manner, as for instance by means of rivets 8. This member 7 is located at a point substantially midway of 105 the length of the casing and is adapted to form a bearing means for the cutting tool as it moves about a horizontal axis in order for its cutting end to pass the end of the casing after the clipping of the rivet head. 110

The casing is made sufficiently large to allow the required freedom of movement of the cutting tool during the clipping operation; the flexible bearing member 7 allowing sufficient give as the tool is caused to pass beyond the housing end of the casing. The flexible portions 6 and 7 serve also as a means for holding the casing in proper position upon the cutting tool.

10 This device is especially adapted for use in connection with a pneumatic gun or other power tool for clipping rivet heads, and as the tool engages the rivet head it bears an angular relation with the length of the casing, as indicated in Fig. 3. Then as the tool clips the rivet head, this angular relation is increased to the extent that the end of the tool passes beyond the end of the casing as indicated in Fig. 4. The head 11 is 15 caught in the housing 9 and is thus prevented from causing injury.

By providing the angular play between the tool and the casing, it is possible to make the casing rigid and at the same time allow the end of the tool to pass beyond the casing. This results in a more durable structure. Then with the reinforcement for the housing, it is prevented from being torn by the force of the rivet head as it flies from the rivet. And furthermore the severed rivet head is prevented from slipping past the edge of the housing, as above explained.

Other advantages will be apparent to those who are familiar with the art to which 20 this invention relates.

What I claim is:

1. A rivet head catcher, comprising a casing member adapted to be applied to a clipping tool or the like, said casing being open 40 and free of obstruction along its one side, a single bearing means provided between the side walls of said casing, and extending across said open side in such a manner that the cutting tool is free to move about said bearing means on a transverse axis during the clipping operation so as to allow the cutting end of the tool to pass beyond the end of said casing as part of the same operation.

2. A rivet head catcher, comprising a 50 rigid bracing member, a covering of flexible material upon said rigid member, said rigid member and the covering therefor together forming a casing for a clipping tool or the like, the side walls of said covering throughout part of the length of the casing extending beyond said rigid member and being free for bending, a yieldable bearing member extending between the side walls of said yieldable extensions and adapted for movement toward and away from said casing.

3. A rivet head catcher, comprising, a concave back part of rigid material, side walls of yieldable material extending from the marginal portions of said back part throughout the rear portion thereof, the marginal

portions of said yieldable side walls being adapted to be snugly embraced about a cutting tool for gripping the same during its operation in said casing.

4. A rivet head catcher, comprising a concave back part of rigid material, said back part being formed at one end with a bulged housing portion to receive the clipped head of a rivet or the like, side walls of yieldable material, said yieldable material extending from the marginal portions of said back part throughout the rear portion thereof, the marginal portions of said yieldable extensions being adapted to be snugly embraced about a cutting tool for gripping the same during its operation in said casing.

5. A rivet head catcher, comprising a concave back member of rigid material, side walls of yieldable material extending from the sides of said concave member, a yieldable bearing member extending between the marginal portions of said side walls, said bearing member being adapted to allow movement of a tool about a transverse axis so as to permit the cutting end of such tool to pass beyond the end of the casing.

6. A rivet head catcher, comprising a concave back member of rigid material, side walls of yieldable material extending from the sides of said concave member, a bearing portion extending between the marginal portions of said side walls, said bearing portion being adapted to allow movement of a cutting tool about a transverse axis so as to permit the cutting end of such tool to pass beyond the end of the casing.

7. A rivet head catcher, comprising a casing member adapted to be applied to a clipping tool or the like, said casing being so constructed as to allow relative movement of said tool for clipping the head of a rivet or the like, said casing including a metal body portion to receive the severed part, said body portion being provided with an extension of yieldable material from the front edge thereof corresponding to the cutting end of the tool and adapted for engagement by the same.

8. A rivet head catcher, comprising a casing member adapted to be applied to a clipping tool or the like, said casing being so constructed as to allow relative movement of said tool for clipping the head of a rivet or the like, said casing including a metal body member to receive the severed part, said body member being provided with an extension of yieldable material from the front edge thereof corresponding to the cutting end of the tool and adapted for engagement by the same, said extension of yieldable material being secured to said metal body at a point out of the path of the severed rivet head or the like.

9. A rivet head catcher, comprising a casing adapted to be applied to a clipping

tool or the like, said casing being so constructed as to allow relative movement of said tool for clipping the head of a rivet or the like, said casing including a metal body member to receive the severed part, a covering of yieldable material upon the forward end portion of said metal body member and secured thereto at a point out of the path of the severed rivet head or the like, said covering extending below the front edge of said metal body member and adapted for engagement by the same.

10. A rivet head catcher, comprising a casing member of yieldable material adapted

to be applied to a clipping tool or the like, 15 said casing being so constructed as to allow relative movement of such tool for clipping the head of a rivet or the like and to permit gripping of yieldable material snugly about the tool, said casing being formed with a 20 rigid reinforced enlarged portion at the end corresponding to the cutting end of the tool and adapted to extend over the tool end so as to receive the severed rivet head or the like.

25

In testimony whereof I affix my signature.

JOHN M. CROWE.
